METHOD OF MAKING STEEL RULE BLANKING DIES AND PUNCHES

Russell J. Tobey, 8796 Fern Glen, Crestwood, Mo.

Filed Feb. 17, 1958, Ser. No. 715,786

3 Claims. (Cl. 76—107)

This invention relates to blanking dies and punches and more specifically to a method of making steel rule blanking dies and punches for use therewith.

For years, efforts have been made to reduce the expense of making blanking dies and punches. One of the results of these efforts has been the development of steel rule blanking dies, which have substantially reduced the "die expense" per unit for comparatively short production runs. Prior to the present invention, punches for use with such dies have been manually filed after being marked by the die. Successful forming of the punch has been dependent on human skills. To make a punch which will hold up even during comparatively short production runs of 50,000 to 100,000 has required the use of expensive tool steel. Because of high cost of tool steel, large-area punches have generally been formed in sections along the periphery of the pattern and the sections fitted together. It has also been necessary to make separate punches for different thicknesses of metal to be blanked.

It is a primary purpose of the present invention to provide a method of making steel rule blanking dies and punches which is inexpensive and not dependent on skilled die makers in forming the punches. It is a further object of the present invention to provide a method of making such dies and punches which will hold up during intermediate length production runs and which will permit the use of metal less extensive than tool steel in the punch. An additional purpose is to provide a method of making such dies and punches wherein the forming of the punch is not dependent on the thickness of the metal to be blanked. Other objects will be apparent from this specification.

Referring to the drawings:

Figure 1 is an exploded perspective illustrating the application of my invention to a die and punch set for blanking oval parts.

The first step in my method is the forming of a template 10 to the shape of the part to be blanked. For a simple die and punch set, as contrasted to a compound die and punch set, this template will also be a template of the punch to be made. The punch template 10 may be formed of a wide variety of metals having various thicknesses, but is preferably formed of mild steel approximately $\frac{1}{16}$ " thick because of the ease with which such sheet metal may be cut. The forming of the template may be accomplished by known methods, as by sawing to the desired shape.

A steel rule dies 17 is then shaped closely around punch template 10. This may be accomplished by placing punch template 10 on a die board 11, scribing a mark 12 along its edge, cutting a plurality of slots 13 in die board 11 along the scribed mark 12, replacing template 10 on die board 11, and fitting a steel rule cutting blade 14 closely around template 10 and driving it into slots 13. The die board 11 may be made of maple approximately $\frac{3}{4}$ " thick, or of any other material of suitable thickness now in use for such die boards.

2

I prefer to cut several slots through the die board, leaving the portion of the die board within the scribed mark 12 joined to the balance of the die board by several bridging portions. This requires the cutting of notches 5 16 in the steel rule cutting blade 14 to fit the bridging portions between the slots 13. To obtain a tight driving fit, it is preferable that slots 13 be narrower than steel rule 14.

While any suitable steel rule cutting blade may be 10 used without departing from my invention, I find that for most applications an 8 or 10 point rule, 1" or $1\frac{1}{4}$ " wide, is desirable. It is usually advisable to shape steel rule cutting blade 14 roughly to template 10 and temper it prior to fitting it closely around template 10 and inserting it into slots 13 of die board 11. The steel rule 14 is driven into slots 13 so that its cutting edge 15 projects from die board 11. The cutting edge 15 of the steel rule 14 preferably tapers inward toward the template 10 and ordinarily is somewhat flattened, depending on the composition and thickness of the metal to be blanked.

The die 17 and punch template 10 are then removably secured in alignment with each other to opposing holders 18 and 19 of a die set, also called die and punch shoes; 25 and a piece of metal 30 larger than template 10 is removably secured to the same die set member as template 10 so as to cover the outer surface of template 10 completely. Die set holders are customarily provided with means for aligned attachment to a punch press, not shown, and one of such holders is provided with aligning pins 20 and the other with corresponding bushings 21. The template 10 and die 17 are secured respectively to back-up plates 22 and 23 with screws 24 and 27; 30 then the back-up plates 22 and 23 are secured to such holders 18 and 19 with bolts 25 and 28 and nuts 26 and 29.

The piece of metal 30 will be blanked to form a punch, as will be hereinafter more fully explained. It may be of various compositions and thicknesses, but I have found that for most applications, an unannealed steel alloy, such as chrome molybdenum, of approximately $\frac{1}{8}$ " thickness, is suitable. The piece of sheet metal 30 has holes bored into or through it in alignment with screws 24, which project through template 10 and secure sheet metal 30 to back-up plate 22 so as to cover template 10.

After the die 17, template 10 and sheet metal 30 have been thus secured to the die set members 18 and 19, I strike sheet metal 30 with the steel rule cutting blade 14, with sufficient force to blank sheet metal 30 between such steel rule cutting blade and template 10. I thus form a punch, not shown, having outer edges substantially coterminous with the inner edges of the cutting blade 14. The striking may be most readily accomplished by attaching holders 18 and 19 to a punch press in the usual manner and activating the punch press with adequate pressure. I find that the pressure required is slightly greater than would be required to blank sheet metal 30 with a standard steel rule blanking die and punch set.

After the punch has been blanked out of sheet metal 30, the punch and the template 10 are removed from back-up plate 22, template 10 is discarded or stored, and the punch resecured to back-up plate 22. The steel rule blanking die and punch set is then ready for use.

It will be recognized that the suitable ranges of the 65 composition and thickness of sheet metal 30 and template 10, the thickness and width of steel rule cutting blade 14, and the degree of flattening of cutting edge 15 are determined by the strength and thickness of the material to be blanked. Generally as the strength and thickness 70 of the metal to be blanked increases, the thickness and strength of the punch required increases, the thickness and degree of flattening of the steel rule increases, and the

required thickness of the punch template increases. However, where the punch template is made of $\frac{1}{16}$ " mild steel and the punch of $\frac{1}{8}$ " chrome molybdenum steel, most metals $\frac{1}{4}$ " thick or less can be accommodated by varying the steel rule between 8 and 10 pt. and varying the degree of flattening of the cutting edge.

While I have illustrated and heretofore described the application of my process to a simple die and punch set, it will be obvious to those skilled in the art that the process may be readily adapted to compound die and punch sets 10 and to combination blanking and piercing die and punch sets, without departing from my invention.

Having thus described my invention, I claim:

1. A method for making a steel rule blanking die and punch set having substantially coterminous inner die edges and outer punch edges, said method comprising the steps of forming a punch template out of sheet metal, inserting a steel rule cutting blade into a die board closely around said punch template, removably and alignedly securing said steel rule cutting blade and said punch template to the opposed members of a die set, removably affixing a larger piece of sheet metal to one of said die set members through said punch template, and blanking a punch out of said larger piece of sheet metal 20 with said steel rule cutting blade and punch template.

2. A method for making a steel rule blanking die and

5 punch set having substantially coterminous inner die edges and outer punch edges, said method comprising the steps of cutting a punch template out of sheet metal, scribing a mark along the edge of said punch template on a die board, cutting a plurality of slots along said mark, fitting a steel rule cutting blade closely around said punch template into said slots, securing over said punch template to a die set member a larger piece of thicker sheet metal, mounting said steel rule cutting blade to the opposing die set member alignedly with respect to said punch template, and striking said thicker piece of sheet metal with said steel rule cutting blade to blank out a punch.

3. The method defined in claim 1, together with the further steps of removing the punch template from the die set member to which it was so secured, and then securing the blanked-out punch directly thereto.
